[57] CLAIM

The ornamental design for a retaining clip for flashlights or the like, as shown and described.

DESCRIPTION

FIG. 1 is a perspective view of a retaining clip for flashlights or the like showing my new design, the flashlight and penny being shown in broken lines for illustrative purposes only;

FIG. 2 is a rear view thereof;

FIG. 3 is a left side view thereof, the right side being a mirror image;

FIG. 4 is a bottom view thereof; and

FIG. 5 is a top view thereof.
